(57) **CLAIM**

The ornamental design for a tire tread, as shown and described.

DESCRIPTION

FIG. 1 illustrates a perspective view of an example embodiment of a tire tread according to the present disclosure; FIG. 2 illustrates a front elevational view thereof; FIG. 3 illustrates a left side elevational view thereof; FIG. 4 illustrates a right side elevational view thereof; FIG. 5 illustrates a fragmentary enlarged front view thereof; FIG. 6 illustrates a second fragmentary enlarged front view thereof;

FIG. 7 illustrates a third fragmentary enlarged front view thereof; FIG. 8 illustrates a cross-sectional enlarged view of the tire tread taken along line 8-8 thereof; and

FIG. 9 illustrates a cross-sectional enlarged view of the tire tread taken along line 9-9 thereof
FIG. 10 illustrates a perspective view of a second example embodiment of a tire tread according to the present disclosure;

FIG. 11 illustrates a front elevational view thereof; FIG. 12 illustrates a left side elevational view thereof; FIG. 13 illustrates a right side elevational view thereof; FIG. 14 illustrates a fragmentary enlarged front view thereof; FIG. 15 illustrates a second fragmentary enlarged front view thereof; FIG. 16 illustrates a third fragmentary enlarged front view thereof; and,

FIG. 17 illustrates a cross-sectional enlarged view of the tire tread taken along line 17-17 thereof.
In the drawings, the broken lines depict environmental subject matter only and form no part of the claimed design. The cross-hatching shown in FIGS. 10, 11, 14, and 15 represents elements of the design having a contrasting texture to that of the surrounding tire tread.
